UNITED STATES PATENT OFFICE.

FURNEY F. GREEN, OF COALGATE, OKLAHOMA.

RAILROAD-TIE.

1,143,188.

Specification of Letters Patent. Patented June 15, 1915.

Application filed October 12, 1914. Serial No. 866,343.

To all whom it may concern:

Be it known that I, FURNEY F. GREEN, a citizen of the United States, residing at Coalgate, in the county of Coal and State 5 of Oklahoma, have invented a new and useful Railroad-Tie, of which the following is a specification.

This invention relates to metallic railway ties, and is designed more especially as an 10 improvement upon the structure shown, for example, in Patent No. 1,069,779, issued to me on August 12, 1913.

One of the objects of the invention is to provide a metallic tie which is durable and 15 efficient in construction and has means combined therewith whereby rails of different sizes can be connected readily thereto.

A further object is to provide means whereby the tie is stiffened both longitudinally and transversely.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a plan view of a tie having the present improvements combined therewith. Fig. 2 is a plan view of one end portion of the tie with the rail brace removed. Fig. 3 is a plan view of one end portion of the tie with the rail chair 40 and the rail fastening means removed. Fig. 4 is a section on line A—B Fig. 2. Fig. 5 is a section on line C—D Fig. 2. Fig. 6 is a section on line E—F Fig. 1. Fig. 7 is a section on line G—H Fig. 2. Fig. 8 is a 45 perspective view of the rail chair. Fig. 9 is a perspective view of said chair inverted. Fig. 10 is a perspective view of the rail brace.

Referring to the figures by characters of 50 reference 1 designates the side members of the tie, the same being formed preferably of sheet metal and being provided adjacent their ends with outstanding bottom flanges 2. The terminals of the side strips or mem-

bers 1 are extended inwardly toward each other as at 3 and provided with inwardly directed flanges 4. These flanges are welded or otherwise secured to intermediate longitudinal partition strips 5, each of which is provided, at one end, with a laterally extended portion 6 having an inwardly directed flange 7. The partition strips 5 are oppositely disposed so that they can be assembled as shown and, when welded or otherwise secured at their ends, will form 65 a one-piece tie body.

The outturned flanges 2 are riveted or otherwise secured to bottom plates 8 on which are formed longitudinal and transverse ribs 9 designed to engage the road bed. 70 These ribs serve to prevent the tie from creeping, either transversely or longitudinally.

Interposed between the side strips 1 and the intermediate or partition strips 5 are 75 channel strips 10 riveted, welded, or otherwise secured to the tie body and the side channel strips 10 have upstanding tongues 12. Another set of channel strips 13 is provided, these strips being located between the 80 side strips 1 and the partition strips 5 and being spaced from the channel strips 10 a distance somewhat greater than the width of the base of a rail of maximum size. These channel strips 13 have short upstanding 85 tongues 14. The space between the channel strips 10 and 13 is filled with series of channel strips 15 forming a cellular support for a rail chair which is adapted to fit snugly between the tongues 12 and 14 and is 90 of the peculiar construction hereinafter described.

Channel strips 15' are welded or otherwise secured in the tie between the strips 1 and the partition strips 5 and are spaced from 95 the channel strips 13 so as to form pockets 16. These pockets are adapted to receive tongues 17 depending from a rail brace 18 such as shown in detail in Fig. 10, and the intermediate tongue 17 has a bolt opening 19 100 for the reception of a bolt 20 which is extended transversely through those channel strips 10, 15 and 15' located between the partition strips 5. When this bolt is in place, the rail brace 18 is held securely in position 105 and the same bolt 20 is also designed to engage a rail fastening plate 21, as shown particularly in Figs. 5 and 6 and has a depend-

ing portion extending between the partition strips 5 while its upper portion is extended above the tie.

As shown in Figs. 8 and 9, the rail chair 5 includes a base plate 22 provided adjacent its outer side with an upstanding longitudinal flange 23 while another shorter upstanding flange 24 is formed longitudinally upon the base plate near its inner side. Depending tongues 25 are provided along the 10 sides of the base plate 22 and are adapted to project into the tie between the partition strips 5 and between the side strips 1. Depending end flanges 26 are also provided to 15 overhang and engage the side strips 1. These rail chairs fit snugly between the upstanding tongues 12 and 14 and are adapted to be made in different sizes and shapes, to adapt them for use in connection with rails 20 of different sizes. For example, where the chairs are to be used in connection with rails of the maximum width, the distance between the flanges 23 and 24 will be equal to the base of the largest rail. Where the chairs 25 are to be used with smaller sized rails, however, the distance between the ribs 23 and 24 must be the same as the width of the bases of the rails.

The bottom face of the chair base 22 is 30 formed with intersecting grooves 27, these grooves being adapted to receive the upper edges of the channel strips 15 and partition strips 5.

In order to attach a rail to the tie, the said 35 rail is placed in position upon the chair so that the sides of its base flanges will fit snugly against the flanges 23 and 24. The upstanding flange 23 is then bent over the outer base flange of the rail by using a 40 sledge, or the like after which the upstanding tongues 14 are bent over into engagement with the adjacent side of the rail chair. The tongues 17 of the rail brace are then inserted into the pockets 16, the brace 18 bearing 45 against the outer side of the rail. The tongues 12 are then bent over the inner side of the rail chair after which an attaching plate 21 is placed in engagement with the tie, the upper portion of the attaching plate 50 lapping the chair, the inner flange 24 thereon, and the inner base flange of the rail. The bolt 20, when inserted through the series of channel strips 15 will hold the rail brace and the fastening plate 21 securely in position.

55 The intermediate portion of the tie can be reinforced by means of channel strips 28 interposed between the side strips 1 and the partition strips 5 and welded or otherwise secured thereto. Any desired number of 60 these channel strips can be used. It is also to be understood that any desired number of longitudinal or partition strips 5 can be employed.

In order that the tie may be properly stiffened 65 throughout its length, the upper edges

of the side strips 1 are formed with in-turned flanges 29 and similar inturned flanges are also provided along the lower edges of the side strips, these lower flanges extending from one plate 8 to the other.

70

What is claimed is:—

1. A metallic railway tie including parallel side and partition strips having laterally extended flanged terminals secured together, and channeled transversely disposed strips interposed between and secured to the side and partition strips and constituting connections therebetween.

2. A metallic railway tie including parallel side and partition strips having laterally extended flanged terminals secured together, and channeled transversely disposed strips interposed between and secured to the side and partition strips and forming a cellular chair support.

3. A metallic railway tie including parallel side and partition strips having laterally extended flanged terminals secured together, and channeled transversely disposed strips interposed between and secured to the side and partition strips and forming a cellular support, and a rail chair bearing downwardly on the support, said chair having intersecting grooves for the reception of the upper edge portions of the said transverse channel strips and the longitudinal partition strips.

4. A metallic railway tie including parallel side and partition strips having laterally extended flanged terminals secured together, channeled transversely disposed strips interposed between and secured to the side and partition strips and forming a cellular support, a rail chair bearing downwardly on the support, said chair having intersecting grooves for the reception of the upper edge portions of the said transverse channel strips and the longitudinal partition strips, and bendable means integral with certain of the channel strips for engaging the chair to hold the same in engagement with its cellular support.

5. A metallic railway tie including spaced longitudinal side and partition strips having offset terminals connected together and constituting spacing means, there being outstanding flanges upon the side strips, spaced plates secured to said outstanding flanges, and channeled strips interposed between said longitudinal side and partition strips and extending transversely of the tie, said channel strips secured to and constituting transverse braces for the longitudinal strips.

6. A metallic railway tie including spaced longitudinal side and partition strips having offset terminals connected together and constituting spacing means, there being outstanding flanges upon the side strips, spaced plates secured to said outstanding flanges, and channeled strips interposed between said lon-

5 gitudinal side and partition strips and extending transversely of the tie, said channel strips secured to and constituting transverse braces for the longitudinal strips, and lon-
5 gitudinally extending reinforcing flanges upon the upper and lower edges of the side strips.

7. A metallic railway tie including longitudinal side and partition strips having lat-
10 erally extended terminal portions secured together to constitute spacing means and to form the end walls of the tie, transversely disposed channel strips interposed between and secured to the side and partition strips
15 and forming a chair support, a chair bearing downwardly upon said channel strips, bendable tongues integral with certain of the channel strips and adapted to engage the side portions of the chair, and a bendable
20 rail engaging flange upon the chair.

8. A metallic railway tie including longi-

tudinally disposed side and partition strips having laterally extended end portions secured together to constitute spacing means and to form the end walls of the tie, strips 25 interposed between and secured to the side and partition strips and coöperating therewith to form a cellular chair support, a chair having intersecting grooves in its bottom face for the reception of the upper edges of 30 the cellular support, tongues depending from the chair and interposed between the side and partition strips, and upstanding rail engaging flanges upon the chair.

In testimony that I claim the foregoing as 35 my own, I have hereto affixed my signature in the presence of two witnesses.
